Primary Examiner—Martie Thompson*Assistant Examiner*—M. Pandozzi*Attorney, Agent, or Firm*—Rhodes & Ascolillo; David L. Baker[57] **CLAIM**

The ornamental design for a beverage container for a bicycle, as shown and described.

DESCRIPTION

FIG. 1 is a left side elevational view of a beverage container for a bicycle;

FIG. 2 is a top perspective view thereof;

FIG. 3 is a front elevational view of a beverage container for bicycle;

FIG. 4 is a left side elevational view;

FIG. 5 is a top plan view of FIG. 2;

FIG. 6 is a bottom plan view thereof;

FIG. 7 is a rear elevational view; and,

FIG. 8 is a right side elevational view.

The broken line showing of a bicycle, bicycle rider, and clips to hold the beverage container is for illustrative purposes only and forms no part of the claimed design.

FIG. 1

FIG. 2

FIG. 3

FIG. 4

FIG. 5

FIG. 6

FIG. 7

FIG. 8
